FLEXIBLE CAMERA MOUNT

Mac L. Olds, 7175 W. 94th St.,
Los Angeles, Calif. 90045

Filed Mar. 29, 1973, Ser. No. 346,143

Term of patent 14 years

Int. Cl. D16—05

U.S. Cl. D61—1 G

FIG. 1

FIG. 2

FIG. 3

FIG. 5

FIG. 4

FIG. 1 is a typical side-elevational view of flexible camera mount showing my new design;

FIG. 2 is a top plan view thereof;

FIG. 3 is a bottom plan view thereof;

FIG. 4 is a sectional view taken along line 4—4 of FIG. 1; and

FIG. 5 is a typical side-elevational view of another embodiment of my new design of FIG. 1 wherein the knurled knob has been grooved and left unchamfered.

I claim:

The ornamental design for a flexible camera mount, as shown and described.
